UNITED STATES PATENT OFFICE.

JAMES PETTIBONE, OF AVONDALE, OHIO.

DESIGN FOR A BUTTON.

SPECIFICATION forming part of **Design No. 20,790, dated June 2, 1891.**

Application filed May 5, 1891. Serial No. 391,677. Term of patent 14 years.

To all whom it may concern:

Be it known that I, JAMES PETTIBONE, a citizen of the United States, and a resident of Avondale, in the county of Hamilton and State of Ohio, have invented and produced a certain new Design for the Face of a Button, of which the following is a specification, reference being had to the accompanying drawings, making a part thereof.

10 Figure 1 is a plan view of a button, illustrating my design. Fig. 2 is a section on line $x-x$, Fig. 1.

The leading feature of the design resides in a convex-faced button having thereupon 15 the following emblems shown in relief: a shield between two men, supported upon the emblems of a horn of plenty and a bee-hive, the figure of a beaver above the shield, and

on the face of the shield are mounted the emblems of a plow, pickax, spade, an anchor, 20 hammer, and arm. One of the men represents a miner, who is holding a pickax, and the other a sailor holding a coil of rope, the whole being in full relief mounted upon the plain convex face of a button. Upon the base of 25 the foreground is a ribbon showing thirteen stars.

What I claim is—

The relief design for a convex button-face, substantially as shown and described. 30

In testimony whereof I have hereunto set my hand.

JAMES PETTIBONE.
